CLAIM

The ornamental design for a massage strap for animals, as shown and described.

DESCRIPTION

FIG. 1 is a top view of my massage strap for animals, the opposite side being a mirror image thereof.

FIG. 2 is right side view of the design, the left side being a mirror image thereof.

FIG. 3 is a left end view elevation of the new design.

FIG. 4 is a right end elevation view of the new design; and, FIG. 5 is a cross-sectional view of the massage strap taken along the lines 5—5 of FIG. 1.
